STITCH LENGTH ADJUSTING MECHANISM

Carl W. Johnson, Brooklyn, N. Y., assignor to
American Machine and Foundry Company, a
corporation of New Jersey

Original application August 12, 1939, Serial No.
289,907. Divided and this application August
11, 1942, Serial No. 454,353

4 Claims. (Cl. 112—210)

1

This invention relates to sewing machines, and the present application is a divisional application from the earlier application, Serial No. 289,907, filed August 12, 1939, for Sewing machine and relates to improvements in mechanism for controlling the length of stitches to be formed during the operation of the machine.

The invention relates further to sewing machines, especially of the under and over stitch type, utilizing a double pointed needle having an eye located between the points, and has particular reference to mechanism for controlling the length of stitches formed by the movement of this type of needle and a thread through work being sewed.

In order to meet all of the demands which may be imposed upon my machine in sewing all of the various kinds of materials which may be handled thereon, it may be necessary from time to time or during the sewing of any particular work or material to change the length of the stitch from long to short or vice versa, or to utilize a certain length stitch for one part and another length stitch for another, etc. For that reason my invention further consists in the provision of improved mechanism which makes it possible to change the length of the stitch from time to time whenever necessary. This mechanism may operate automatically or be adjusted manually to change the length of the stitch whenever desired.

It is a further object of my invention to provide improved mechanism for use with a machine employing a double pointed needle in which changes in stitch length are made automatically during the operation of the machine.

It is also an object of my invention to provide mechanism which automatically changes alternate stitch lengths during the operation of the machine.

It is also an object of my invention to provide a sewing machine of the type forming over and under stitches of a predetermined length, and selective means for changing from one length to another either manually or automatically.

With these and other objects not specifically mentioned in view, the invention consists in certain combinations and constructions which will be hereinafter fully described, and then specifically set forth in the claims hereunto appended.

In the accompanying drawings which form a part of this specification, and wherein the several reference characters designate the same or like elements:

2

Figure 1 is a partial front elevation of the sewing machine embodying my improved stitch length controlling mechanism;

Figure 2 is a detail view taken on line 2—2 of Figure 1 showing one form of the feeding mechanism and means for adjusting the feed to lengthen or shorten the stitches;

Figure 3 is a side elevation of a modified device for adjusting the length of stitch;

Figure 3a is an end view of a detail of the mechanism shown in Figure 3;

Figure 4 is a side elevation of another modification for adjusting the length of the stitch in which it is possible to produce alternate short and long stitches automatically;

Figure 5 is an end view of Figure 4;

Figure 6 is a sectional partial side elevation of a detail of the work feeding mechanism taken on line 6—6 of Figure 1; and

Figure 7 is a plan view of a detail of the stitch length adjusting mechanism shown in Figure 3.

Referring to the drawings, Figure 1 shows a preferred embodiment of my invention adapted for use in a machine of the type employing a double pointed needle N having an eye between the points and needle bars 55, 56 provided with tapered caps 72 serving to confine spring pressed jaws (not shown), which may be of the type shown in Naftali Reissue Patent No. 19,653, granted July 23, 1935, which clutch the needle N, to perform the stitching. As shown, the machine comprises a stationary frame 10, a sewing machine head 11 extending therefrom and a bracket 12 supporting the work table 13. Hand wheel 41 is driven in the manner described in my co-pending application to operate the needle bars and associated mechanism from a suitable motor and clutch (not shown) by means of a pulley 24, driven by means of a belt 23 running

30 on a pulley 22 carried by shaft 36 which mounts a pulley 19 over which runs a motor driven belt 18.

It will be understood by those skilled in the art, that in this type of machine, needle N is projected back and forth through the work and is, therefore, alternately grasped by the jaws of each needle bar 55, 56. Briefly the action is such that as one needle bar, say 55, moves needle N downwardly into the work, the head 73 of the needle bar 55 will abut the upper lug 63 and effect the release of the needle from the upper needle bar, the needle bar being grasped by the lower needle bar 56 in the same manner as the upper bar. The upper needle bar upon receiving 50 the needle from the lower needle bar 56, rises

and elevates head 73 from engagement with lug 63. At the moment this occurs, the spring pressed jaws clutch the needle by reason of the spring action in needle bar 55, and movement of the jaws into cap 72. The operation of the lower needle bar 56 is effected in the same general manner, and hence it will be understood that whenever a head 73 is not in engagement with a lug 63, the spring action in each needle bar will force the gripping jaws into cap 72 and cause the jaws to grip the needle. The spring action of the jaws acts alternately so that first one and then the other bar grips the needle.

The work is fed over table 13 beneath a presser foot 75 provided to engage and retain it in sewing position. This foot is secured to a holder 76 clamped to the lower end of a spring tensioned rod 77 which is guided in the lugs 63 and 64 of member 65. The rod 77 is provided with a block 78 fitting in the space between the rear wall of member 65 and a strap 79 secured to a portion of member 65 and in this manner tends to retain the presser foot in alignment with the needle bars. The upper end of the rod 77 is provided with a collar 80 normally abutting a forked block 81 fastened to one end of a pivot shaft 82. One end of shaft 82 is mounted on a projecting lug 83 of member 63 and has its other end mounted in a lug (not shown) secured to the wall 27 of head 11. At a point along the length of shaft 82 is mounted an actuator arm 86 carrying a stud supporting a head 87 which holds one end of a rod 88 connected to a link (not shown) in turn connected to a manually operated shift plate (not shown) all as shown and described in my co-pending application, Serial No. 289,907 in order to raise and lower foot 75. By lifting the presser foot the operator may readily inspect the work or locate new work in sewing position.

When the lower needle bar 55 ascends, causing the needle N to push the thread through the work, the sudden thrust or piercing tends to overcome the spring pressure of rod 77 and lift the presser foot 75 from the work. It is desirable to have the spring 95 of rod 77 weak enough to allow the presser foot to yield upwardly in order to allow the work to be readily manipulated, and to prevent undue pressure on the work. In order to overcome any excess upward movement thereof, a spring actuated arm 96 may be provided, which is in close relationship with the upper end of rod 77 so that the rod in moving upward will strike the end of the arm 96, and be forced back, thereby tending to hold the presser foot 75 in proper operative position relative to the work. Arm 96 is mounted on a pivot stud (not shown) carried by a bar 98 suspended from head 11 and is urged by a spring (not shown) downwardly to hold an adjusting screw 101 in abutment with a suitable stop (not shown). The screw 101 is provided so that the gap between rod 77 and arm 96 may be varied to best suit conditions and when properly set the screw is locked in position by any suitable means, such as a knurled nut 103.

Referring to Figure 1, the mechanism for pulling the loop as formed from the thread will now be described briefly since it forms no part of this invention. A gear 175 meshing with the gear 44, but rotating at a greater speed, is fixed to a shaft 176 mounted in suitable bearings 177 of head 11 and of a stationary member or drum 178 suitably supported by head 11 and frame 10. A gear through suitable driving connections shown and described in my co-pending applica-

tion, drives the thread puller 186 in order to pull the loose end of the thread through the work. The thread puller 186 is provided with a pointed thread engaging end so mounted that it may rotate around the periphery of the stationary drum member 178. The chief function of the thread puller is to engage the loop of thread formed on alternate movements of the needle and pull the thread through the work, and dispose it about the periphery of the drum in such a manner that the danger of snarling, fouling or breaking the thread is practically eliminated. Thread puller 186 is fixed to the outer end of a carrier arm 187, which is pivotally mounted on a rotating member (not shown). The outer end of arm 187 is also provided with a curved guide plate 193 adapted to engage a tape 194 partly circling the drum 178, which tape acts to maintain the thread in orderly fashion and also prevents whipping of the thread as it is placed around the drum. A brush S may be fixed beneath the drum 178, as shown in Figure 1, in order to act as a brake and apply a frictional force upon the thread as it is being pulled from the drum. This adds additional control in handling the thread and prevents it from whipping about or tangling in any manner.

The driven sprocket 42 (Figure 1) imparts motion to a chain 105 running over a sprocket 106 mounted on a shaft 107 supported in a hub of bracket 108 secured to frame 10. The opposite end of shaft 107 supports a coupling 109 (Figure 2) terminating in a cam surface 110 which imparts up and down motion to the material feed to be described hereinafter. Member 109 supports a short eccentric stud 111 equipped with a roller 112 engaging an elongated slot 113 provided in the lower end of lever 114 fulcrumed on arm 115 which is mounted on the end of a pivot stud 116 secured to frame 10 by a bolt 117. Lever 114 mounts a stud 118 carrying a follower 119 engaging a slot 120 in the head of a slotted member 121 mounted in a counterbored portion 122 of plug 123 turnably supported in an aperture of frame 10.

By loosening the thumb screw 126, arm 124 may be moved, and in so doing shift the position of slot 120 in member 121, thereby changing the angular relation of slot 120 and lever 114. Arm 124 is provided with an arcuate slot 125 in order to allow said arm to be moved relative to loosened screw 126 in order to adjust the position of member 120 and secure the slot 121 therein in any desired adjusted position relative to follower 119. It will be apparent, therefore, that the more slot 120 is turned towards the vertical, the greater will be the feeding motion of plate 135 due to the fact that lever 114, which is pivoted upon lever 115, will be raised a greater amount; lever 115 also will be rocked a proportionately greater amount. If it be desired to decrease the movement of plate 135, the slotted member 121 will be adjusted in the opposite direction so that the slot therein will be moved more towards the horizontal. Since lever 115 is fastened to a fork 127 (Figure 2) connected to a material feed arm 128, the resulting to and fro motion imparted to arm 128 can be varied, thereby making it possible to adjust the length and make longer or shorter stitches as required. The up and down movement of arm 128 is imparted by a cam 110 with which coats a cam follower 129 provided on an arm of lever 130 loosely mounted on stud 121a. The arm 131 of the lever supports one end of an adjustable link

132 which is connected to a depending arm 133 of member 128. The right end of arm 128 (Figures 1 and 6) is mounted on a pivot stud 140 supported in lug 141 of an arm 142 loosely mounted on stud 134. One end of this stud is mounted in a spacing block 143 suitably secured to frame 10.

Material feed plate 135, attached to arm 128, is provided with a corrugated or toothed work feeding surface adapted to engage and advance the work. This plate may be of the usual type employed in sewing machines and is arranged to project upwardly through a slot in plate 13 over which the work is fed to and from the needle. As each stitch is completed, the arm 128 through its connections, is caused to index, that is, the arm descends slightly below the level of throat plate or table 13 leaving the work resting thereon and then the arm moves up, engages and advances the work in readiness for the next stitch, the work remaining in this position while the plate 135 returns to its original position.

Referring to the modification shown in Figure 3, the general operation of the feed arm 128 is the same as hereinabove described. Mechanism has been provided, however, to make adjustments in order to control the stitch length for normal stitching, and also make longer or shorter stitches as the case may be according to the requirements with respect to the particular work being sewed. As an example, in sewing the sides of the fingers of gloves, a normal stitch length is generally used for the major portions of each glove. However, when the operator proposes to sew the tip portion of the fingers, the normal stitch may be found to be too long for satisfactory work, and hence means is provided for quickly shortening the stitch length. At this time, the operator depresses a foot pedal 308 which through connections to be described presently, shifts the position of the slotted stitch control member 121 to produce shorter stitches for sewing the finger tip portion of the glove. When the sewing of the tip portion is completed, the operator's foot is released from the pedal and normal stitching will be resumed.

An arm 300 (Figure 3) is clamped to member 121 and at its lower end supports a forked head 301 and a head 302 connected by means of a rod 303 to an arm 304 fixed on a pivot shaft 305. An arm 306, also fixed on shaft 305, is actuated by a link 307 connected to a foot pedal 308 mounted on a pivot 309. The forked head 301 carries an adjustable link 310 which at its other end is provided with knurled nuts 311 and 312 which are turnably and slidably mounted in an aperture 313 of a holder 314 secured in a suitable manner to the frame of the machine. The aperture 313 is open at the top and exposes a portion of the shanks 315 of the nuts 311 and 312, the exposed portion of the shanks being engaged by prongs of a flat spring 316 which tend to hold said nuts from turning after the final adjustments have been made.

The knurled nut 311 provides means for adjusting the position of member 121 to obtain the length of stitch best suited for different types of work. A spring 317 having one end attached to arm 304 and its other end secured to a stationary part of the machine (not shown) normally tends to hold the shoulder 318 of nut 311 in engagement with holder 314. The knurled nut 312 governs the length of the short stitch. That is, with the foot pedal 308 depressed the rod 303 will move arm 300 and consequently change the 75

position of member 121 by varying the throw of lever arm 114 which controls the horizontal distance traveled by bar 128. The movement of arm 300 causes link 310 to remove the shoulder 318 of nut 311 from holder 314 and advance nut 312 until its shoulder 319 abuts the other end of holder 314 thus halting further movement of arm 300. Member 121 retains this position until the foot pedal 308 is released, whereupon spring 317 restores the device to its former position. It will be apparent that the greater the distance between shoulder 319 and the end of the holder 314, the greater will be the movement of arm 300 to set member 121, which consequently results in shorter stitches.

Referring to Figures 4 and 5, another modified stitch control device is shown in which alternate short and long stitches are automatically produced for decorative work. According to this embodiment, a driven sprocket 320 fixed on a shaft 321 imparts motion to the eccentric 111 and cam 110 to actuate the material feed arm 128 in the same manner as shown in Figures 1, 2 and 3. A gear 322, fixed on shaft 321, meshes with and drives a gear 323 and its attached gear 324 loosely mounted on stud 121a, while the gear 324 in turn drives a gear 325 and a cam 326 loosely mounted on shaft 321. In this manner, the gearing 322, 323, 324 and 325 drives the cam 326 at one-half the speed of cam 110. Cam 326 engages a cam roller 327 carried by a cam lever 328 mounted on shaft 121. Lever 328 is adjustably attached to an arm 329, clamped on shaft 121 by a thumb screw 330. The lower portion of arm 329 is provided with an elongated slot 331 adapted to engage thumb screw 330. By loosening the thumb screw 330, the arm 329 may be moved and in so doing shift the position of slot 120 of shaft 121 resulting in more or less movement of arm 128, as heretofore mentioned.

The cam 326 has a high portion 332 and a low portion 333, the surface 332 being considerably longer than 333 and therefore when it engages follower 327 it holds the slotted head of stitch control member 120 in a position to produce a long stitch, as the follower 327 rides off surface 332 and approaches surface 333, the slotted head of member 120 is turned to a position to produce a short stitch. The continuous rocking of the slotted head results in alternate long and short stitching of the work.

In the mechanisms hereinabove described it will be evident that I have provided means for forming stitches of a predetermined length, and selective mechanism operative either manually or automatically to vary the stitch length by control of the work feeding device in accordance with the wishes of the machine operator or the demands of a given piece of work being sewed or decorated.

The invention above described may be varied in construction within the scope of the claims, for the particular device, selected to illustrate the invention, is but one of many possible concrete embodiments of the same. It is not, therefore, to be restricted to the precise details of the structure shown and described.

What is claimed is:

1. In a sewing machine, a work support, means for feeding work to be sewed along said support including a work feed bar, and mechanism for varying the amount of movement of said means, said mechanism comprising a lever associated with said bar, a second lever pivoted on said first-named lever, means for oscillating said sec-

ond lever, a follower carried by said second lever, a slotted member normally engaging said follower, an adjusting rod secured to said member, adjusting means connected to said rod for setting the length of stitch to be made at a predetermined length, a manually operated device attached to said member for shifting said member to change the stitch from one length to another at the will of the operator while maintaining the adjustment of said adjusting means undisturbed, and means for automatically moving said device in the opposite direction to reset said member in its original adjusted position.

2. In a sewing machine, the combination with a work support, of mechanism for feeding work to be sewed along said support, means associated with said mechanism for adjusting the length of stitch to be made, said means including a stitch length control member, means for setting said member to form stitches of various lengths, an arm fixed to said member, an adjusting rod, a connection between said arm and one end of said rod, a holder supporting the other end of said rod, adjusting nuts on said holder supported end of said rod, said nuts being located on said rod at opposite sides of said holder, means for securing said nuts in adjusted position on said rod and relative to said holder, one of said nuts being adjustably positioned on said rod to control the position of said member for forming a predetermined normal stitch length, means normally holding said nut in engagement with said holder, and manually operated means for moving said member to displace said rod and said one of said nuts from said holder and cause said other of said nuts to engage said holder whereby to modify the movement of said feeding mechanism and thereby control the length of stitch formed.

3. In a sewing machine, a work support, means for feeding work to be sewed along said support

including a work feed bar, and mechanism for varying the amount of movement of said means, said mechanism comprising a lever associated with said bar, a second lever pivoted on said first-named lever, means for oscillating said second lever, a follower carried by said second lever, a slotted member normally engaging said follower, means for shifting the position of said slotted member to vary the extent of movement of said lever and travel of said feeding means, and a manually adjustable device connected to said member for setting the stitch length within predetermined limits, said device including a rod attached to said member, a block slidably mounting one end of said rod and adjustable nuts mounted on said rod at opposite ends of said block.

4. In a sewing machine, a work support, means for feeding work to be sewed along said support including a work feed bar, and mechanism for varying the amount of movement of said means, said mechanism comprising a lever associated with said bar, a second lever pivoted on said first-named lever, means for oscillating said second lever, a follower carried by said second lever, a slotted member normally engaging said follower, means for shifting the position of said slotted member to vary the extent of movement of said lever and travel of said feeding means, a manually adjustable device connected to said member for setting the stitch length within predetermined limits, said device including a rod attached to said member, a block slidably mounting one end of said rod and adjusting screws mounted on said rod at opposite ends of said block, a second rod also attached to said member, and manually operated means operative at will for moving said second rod and shift the position of said member for changing the stitch length within said set limits.

CARL W. JOHNSON.
